UNITED STATES PATENT OFFICE

GEORGE BINET DOREY, OF EVANSTON, ILLINOIS

LATCH

Application filed February 6, 1928. Serial No. 252,269.

My invention relates to improvements in latches.

My improved latch is adapted for fastening relatively movable closure members and especially for use in connection with pivotally mounted closures such as are employed with refrigerators, stoves, furnaces, ovens, ventilators or dumping doors for hopper cars, end gates for waggons and motor trucks and in fact wherever tightly and positively closed doors are necessary.

An object of my invention is to produce a latch embodying a bodily movable latch bolt and a toggle joint connection between said latch bolt and associated closure member whereby the latch bolt, when in operative latching position, will be automatically secured against bodily movement.

Another object of my invention is to utilize the greatly multiplied mechanical advantage obtained by the closing action of a toggle joint mechanism for the purpose of forcing a latch bolt into tight wedging engagement with an associated keeper having a flared opening for the reception of the latch bolt.

Another further object of my invention is to provide a closure fastener having a movable latch bolt adapted for engagement with a keeper and to provide means whereby such latch bolt will be secured against movement when in operative latching position and further provide means for temporarily displacing the bolt from such normally secured position for the purpose of effecting engagement between the said latch bolt and associated keeper.

My invention further resides in certain other details of construction and improvements of parts such as will be more particularly pointed out hereinafter and claimed.

For further comprehension of my invention reference may be had to the accompanying drawings wherein Fig. 1 indicates a vertical side elevational view of a portion of a refrigerator door and door frame with my improved latch incorporated therein, the parts being shown with the door in closed position and the latch mechanism in closure retaining position. Fig. 2 is a vertical side elevational view of the structure illustrated

in Fig. 1, the parts being shown as viewed from left to right. Fig. 3 is a view similar to Fig. 2 except that the door is shown with the latch bolt in latching position on the outer side of the keeper, the parts as positioned indicate the establishment of contact between the latch bolt and its associated keeper during the door closing operation. Fig. 4 is a view similar to Fig. 3 except that the closing operation of the door is somewhat more advanced with the toggle joint broken and the latch displaced from its latching position. Fig. 5 is a view similar to Fig. 4 but with the door closing operation still further advanced and the latch bolt sufficiently displaced from its latching position to clear the keeper. Fig. 6 is a view similar to the three preceding views but with the latch in engagement with the retaining shoulder on the keeper. Fig. 7 is an end vertical elevational view of a dumping motor truck showing my improvements applied to the swinging end door. Fig. 8 is a side fractional elevational view of the truck shown in Fig. 7, the view showing so much of the body as necessary to show the end door in closed and fastened position.

In the construction shown in Figs. 1-6 inclusive, A indicates a closure frame, B the closure, C latch mechanism carried by the closure, and D a keeper carried by the closure frame. The latch mechanism C preferably includes a support or casing 10 having base portions 11-11 whereby the casing is secured to the closure as at 12. Extending outwardly from said base portions 11-11, the main body of the casing is formed of a pan shaped portion which includes an overlying wall portion 13 spaced an appreciable distance from said base portions, and vertically and horizontally extending walls as indicated at 14 and 15 respectively, each of the vertical walls having an elongated slot 16 formed therein. A link 17 extends the entire width between the vertical walls 14 and is pivotally mounted to the casing on a pivot 18 which extends through the vertical walls 14 and is riveted on the outer side thereof as shown at 19, said link is preferably formed of strip metal bent at each end to present loops as indicated at 20 and 21. Pivoted to

the lower end of the link on loop 21 is a bodily movable latch bolt 22 having trunnion like portions 23 extending through the elongated slots 16, said latch bolt 22 is provided 5 with a plurality of arms 24 through which the pivot 25 extends and whereby connection is effected between the link and latch, the pivot 25 is disposed at an appreciable distance from the center or axis of the trunnions thereby providing a fulcrum for the latch bolt. One of the trunnions 23 is extended outwardly beyond the casing and beyond the edge of the closure with which said latch mechanism is associated for the purpose 10 of engaging with the keeper D, and beyond said keeper engaging portion of the bolt there is a finger 26 fixed relatively to the said bolt for the purpose hereinafter described. The opposite end of said latch bolt is provided 15 with an operating handle 27 which is adapted to gravitate by its own weight to a substantially vertical position and assist to maintain the latch bolt in the lower portion of the slots. A torsion spring 28 is wound around pivot 25 and the ends of said spring 29 and 30 respectively abut against the link 17 and latch bolt 22, the torsion in the spring tending to open the joint between the link and bolt and thus positively maintain the latch bolt in the 20 lower portion of the slots.

The keeper D is provided with a base portion 31 whereby attachment is effected with the closure frame A and a web 32 extends outwardly from said base portion, said web 35 having a shoulder 33 which tapers outwardly and upwardly as indicated at 34, thus presenting a flared opening for the reception of the latch bolt 22. On the outer side of the keeper a lateral extension 35 extends 40 in the path of movement of the finger 26. Assuming the latch bolt to be positioned in the lower portion of the slots 16 as the closure is moved towards closed position, the operation of the mechanism is as follows;— 45 the closure is moved towards the keeper until the finger 26, which is curved as indicated at 36, engages with the extension 35 on the keeper as indicated in Fig. 3. Continued movement of the closure in a closing direction will rotate the latch bolt causing pivotal movement thereof about the fulcrum 25 with a consequent bodily movement of the said latch bolt as indicated in Fig. 4. Further turning movement of the latch bolt is 50 continued until such time as the trunnion 23 is elevated sufficiently to pass above the shoulder of the keeper D as indicated in Fig. 5, when further movement of the closure allows the latch bolt to drop rearwardly of 55 the shoulder as indicated in Fig. 6, from which position the torsion of the spring 28 combined with the weight of the latch bolt and its associated handle will force the latch bolt downwardly into the notch forcing the 60 closure still more tightly closed by reason of the flared entrance presented by the tapering shoulder. Should extraordinarily tight door joints be required as in connection with refrigerators, it will be understood that the tension of the spring and the weight of the parts will hardly suffice to force the latch bolt to its final closed position but sufficient turning movement will be exerted to bring the latch trunnion rearwardly of the shoulder and maintain the closure in a partially closed position, from which position a relatively small turning effort on the handle will complete the closing and fastening operation. The use of the pivoted link as the fulcrum for the bodily movable latch member combines stability with few parts and provides for rapid multiplication of mechanical advantage in forcing the closure to its final closed position inasmuch as the motion represents the closing action of a toggle joint which in the final position of the latch mechanism maintains the latch against bodily displacement unless such movement be positively initiated by a rotary movement of the latch bolt. In the final latching position of the latch bolt, as will be seen by reference to Fig. 2, the fulcrum 25 at the junction of the link and latch bolt lies in a straight line on dead center between the axis of trunnion 23 and the pivot 18 of the link with the casing, thus making the latch mechanism self securing and providing the extreme possible multiplication of power to force the latch bolt to its final latching position. The keeper D is beveled on its upper surface as indicated at 37, and between said bevel and the shoulder there is a flat portion 38 on which the trunnion 23 is adapted to ride before making contact with the shoulder 33, the function of said bevel and flat portion being for the purpose of sustaining the latch bolt in its open position independently of the finger 26 and its associated engaging portion 35 on the keeper, and thus provide sufficient clearance between the extreme end of the finger 26 and the lateral extension 35 on the keeper preventing fouling of the parts on the opening movement of the closure. 100 To open the closure from the position in Fig. 2, the handle 27 is moved outwardly thus turning the latch bolt and imparting a bodily movement thereto in an upward direction until such time as the latch bolt will contact with the upper portion of the slots 16 at which time the handle will be in a substantially horizontal direction and a forward pull on said handle will open the door. 110 It will thus be seen that my improved latch consists of only a few parts, is automatic in operation, secured against bodily movement in its closed position and can only be released in the authorized manner, that is, by exerting a turning movement on the handle. 115 In the embodiment of my invention shown 120 125 130

in Figs. 7 and 8 my improvements are shown as applied to the swinging end gate of a dumping motor truck. In said drawings A indicates the side walls, B the end gate, C a keeper, D the latch mechanism and E indicates a pivoted cam adapted to engage with the latch bolt or rod. Each side A is formed of a plate 100 and top and bottom marginal reinforcements as indicated at 101 and 102 respectively, said top reinforcement having a hinge butt 103 for the end gate. The end gate B is formed of a plate 104 having horizontally extending marginal reinforcing flanges as indicated at 105 and 106 respectively and vertically extending marginal reinforcing flanges as shown at 107. There are two keepers C per end gate and a latch mechanism D associated with each keeper but as the construction is the same at each end of the gate, the description hereinafter following will be confined to one end only. The keeper C is formed with a flared recess having a shoulder 108 and a laterally extending projection 109 extending outwardly therefrom, said keeper being preferably secured to the related side wall A by means of rivets 110. The latch mechanism D includes a housing 111 having walls 112 and 113 spaced apart, the latter being extended beyond wall 112 and formed with an elongated slot 114, said housing is secured to the end gate by means of rivets as indicated at 115 and 116. Pivotally mounted between said walls on pivot 117 is a link member 118 and pivoted to said link is a latch member 119 which is formed with double arms 120-120 which straddle the link 118. Outwardly of said arms 120 there is a trunnion portion 121 which extends through the slot 114 and engages with the shoulder 108 of the keeper C and beyond the said keeper engaging portion of the trunnion there is fixedly mounted on the latch a curved finger 122 adapted to engage with the projection 109 on the keeper for the purpose of inducing a rotary movement of the latch mechanism as the end gate is moved towards closed position.

The latch mechanisms at the respective ends of the gate are caused to function in unison by a shaft 123 which extends through the said latch members and is rigidly united therewith, said shaft is preferably of square section and on one end thereof an operating handle 124 is mounted and the opposite end of the shaft is extended beyond its associated latch member for the purpose of providing a suitable extension which may be engaged by a wrench or other operating tool for rotating the shaft. Cooperating with said shaft to further secure the same against bodily movement is the cam E which is pivotally mounted on a bracket 125 on pivot 126.

The cycle of operations is similar to that described in connection with the embodiment illustrated in Figs. 1 to 6 inclusive except that the spring for forcing the parts to closed

position may be omitted in view of the additional weight provided by the shaft 123.

While I have shown and described preferred embodiments of my invention it is to be understood that the same are merely illustrative and I contemplate all modifications which come within the scope of the claims.

What I claim is:

1. As an article of manufacture, a latch mechanism including: a keeper and a latch device having a housing and toggle link mechanism formed of two members, one of such members including a link pivoted to the housing and the other of such members being bodily movable and fulcrumed to the link; guiding means acting on the bodily movable member at an appreciable distance from its fulcrum; and a keeper engaging latch element fixed relatively to the bodily movable member adjacent to the guiding means, said keeper being adapted to engage the bodily movable member to maintain the closure in closed position.

2. As an article of manufacture, a latch mechanism including: a keeper and a latch device having a latch element engageable with the keeper, said latch device including: a housing; a link pivoted to the housing; a lever pivotally connected to the link, said lever having the keeper engaging latch element fixed relatively thereto and movable in unison with the lever; slots in the housing for causing the latch element to travel in a non-circular path; said link and lever cooperating to form a toggle joint adapted to automatically maintain the latch element against bodily movement; and means for operating the toggle joint by a turning movement of the lever.

3. As an article of manufacture, a latching device including a keeper and latching mechanism having a latch element engageable with the keeper, said latch mechanism including: a support; a link pivoted to the support; a lever fulcrumed at one of its ends to the link, said lever having an operating handle extending outwardly from the fulcrum and a trunnion extending laterally from said lever, said trunnion being disposed intermediate the fulcrum and the operating handle and constituting the latch element; and an elongated slot on the support within which the trunnion is adapted to have reciprocatory movement, said link and lever cooperating to form a toggle joint adapted to wedge the trunnion into cooperating engagement with the associated keeper on movement of the lever.

4. As an article of manufacture, a latching device including a shouldered keeper and latching mechanism having a latch element formed with a locking portion adapted to engage with and seat rearwardly of the shoulder on the keeper; said element being adapted to automatically assume a latching position, said latching device including a support; a

- lever fulcrumed at one of its ends relatively to the support and having an operating handle on the outer end of said lever, said lever having the shoulder engaging portion fixed relatively thereto and disposed intermediate the fulcrum and handle; and guideways associated with the support within which the said latch element is adapted to have reciprocatory movement on movement of the lever.
- 5 5. In a latching device, the combination with a closure frame and a closure; of a shouldered keeper mounted on one of said parts; and latch mechanism mounted on the other of said parts, said latch mechanism including: a support; a link pivoted to the support; a lever fulcrumed at one of its ends to the link and having an operating handle outstanding from said fulcrum, said lever having a latch element fixed relatively thereto and formed
- 10 20 with a latching portion disposed intermediate the fulcrum and handle, said latching portion being adapted to seat rearwardly of the shoulder of the keeper to maintain the closure in operative latching position; elongated
- 15 25 slots on the support within which the said element is adapted to have reciprocatory movement on movement of the lever; said link and lever in cooperation with the guideways forming a toggle joint to maintain the latch
- 20 30 element in latching position; and a resilient element acting on the link and lever to urge the latch into latching position.
6. In a latching device, the combination with a closure frame having an opening and
- 35 35 a closure for sealing the opening of a keeper carried by one of the parts; a bodily movable latch member carried by the other of said parts and cooperable with the keeper for maintaining the closure in fastened position;
- 40 40 and means for imparting a movement of translation to the latch member by a turning movement of the said latch member, said means embodying a variable leverage connection between the latch member and the closure member on which said latch member is mounted whereby an increasing ratio of mechanical advantage is obtained as the latch member is urged towards final adjusted position.
- 45 50 7. In a latching device, the combination with a closure frame and a closure; of a keeper mounted on one of said parts; a support mounted on the other of said parts, said support having elongated guideways formed
- 55 55 therein; a link pivoted to the support, said link being disposed intermediate the guideways; and a bodily movable latch member pivoted to the link, said member including axially aligned trunnions, said respective
- 60 60 trunnions extending through the elongated guideways on the support, one of said trunnions being adapted to engage with the keeper for maintaining the closure in fastened position and the other of said trunnions having an operating handle fixed relatively
- thereto, said trunnions being adapted to have movement in the guideways on movement of the handle.
8. In a latching device, the combination with a closure frame and a movable closure; of a keeper mounted on one of said parts; a support mounted on the other of said parts; a link pivoted to the support; a bodily movable latch member pivoted to the link, said last named member having a portion extending beyond the associated closure member and adapted for engagement with the keeper for maintaining the closure in closed position; guiding means associated with the support and latch member for maintaining the latter against movement in the direction of movement of the closure; and means for normally urging the latch into latching position, said means being adapted to automatically maintain the latch against bodily movement when in operative latching position other than by a turning movement of said latch member.
9. In a latching device, the combination with a closure frame and a closure; of a keeper mounted on one of said parts; a link pivotally mounted on the other of said parts; a bodily movable latch pivotally attached to the link, said latch being adapted to engage with the keeper to maintain the closure in closed position; guiding means for maintaining the latch against movement in the direction of movement of the closure; means for normally urging the latch to final adjusted position and automatically securing the latch against bodily movement; and means for automatically displacing the latch from its final adjusted position as the closure is moved to closed position.
10. In a latching device, the combination with a closure frame; of a movable closure; a keeper mounted on the frame; a bodily displaceable latch element mounted on the closure, said element having a portion projecting beyond an edge of the closure for engagement with the keeper on the frame, said element being adapted to be moved into engagement with the keeper by a turning movement of the said latch element; and means for restricting lengthwise movement of the latch element whereby the extent of latch projecting beyond the edge of the closure will be constant throughout the entire movement of the latch element.
11. As an article of manufacture, a latch mechanism including: a shouldered keeper and a latch device, said latch device having a latching portion engageable with the shoulder of the keeper; said latch device including: a base member, a link pivoted to the base member, a lever pivotally connected to the link, said lever having the shoulder engaging portion fixed relatively thereto and movable in unison with the lever; and guiding means associated with the base member and the

shoulder engaging portion of the latch member for confining the path of movement of the latter within a predetermined path.

12. In a latch mechanism for a door adapted to close an opening, the combination with a door frame; of a keeper carried by one of the parts and a latch carried by the other of the parts, said latch having a keeper engaging portion adapted to move into engagement with the keeper for retaining the door in closed position; means for confining the movable latch portion to a given path; and means adapted to automatically assume a position in the path of movement of the movable part of the latch to restrain the latter against movement in an opening direction.

13. In a latching device, the combination with a closure frame and a closure; of a keeper mounted on one of said parts; and a latching element mounted on the other of said parts, said element being adapted to have a bodily movement relatively to its associated closure member; a link pivotally mounted on the closure member on which the latching element is mounted, said link being pivotally united with the latching element; guiding means for restricting the latching element to a straight line path during its bodily movement; said latching element being adapted to engage the keeper for maintaining the closure in closed position, said link and latching element co-operating to form a toggle joint for maintaining the latch element in latching position; and means associated with the keeper and latching element for breaking the toggle joint and displacing the latching element from its latching position as the closure is moved towards closed position.

40 In witness that I claim the foregoing I have hereunto subscribed my name this 23rd day of January, 1928.

GEORGE BINET DOREY.
